UNITED STATES PATENT OFFICE.

OLIVER S. ATTERHOLT, OF FROSTBURG, MARYLAND.

DESIGN FOR A GOBLET OR SIMILAR ARTICLE OF GLASSWARE.

Application filed June 8, 1926. Serial No. 17,983. Term of patent 7 years.

To all whom it may concern:

Be it known that I, OLIVER S. ATTERHOLT, a citizen of the United States, residing at Frostburg, in the county of Allegany and State of Maryland, have invented a new, original, and ornamental Design for a Goblet or Similar Article of Glassware, of which the following is a specification, reference being had to the accompanying drawing, forming part thereof.

The figure is an elevation of a goblet showing my new design.

I claim:

The ornamental design for a goblet or similar article of glassware, as shown.

OLIVER S. ATTERHOLT.
